UNITED STATES PATENT OFFICE.

GEORGE HEIMLICH, OF SYRACUSE, NEW YORK.

ROTARY ALBUM.

SPECIFICATION forming part of Letters Patent No. 623,603, dated April 25, 1899.

Application filed June 10, 1898. Serial No. 683,093. (No model.)

To all whom it may concern:

Be it known that I, GEORGE HEIMLICH, of Syracuse, in the county of Onondaga, in the State of New York, have invented new and useful Improvements in Rotary Albums, of which the following, taken in connection with the accompanying drawings, is a full, clear, and exact description.

This invention relates to improvements in cabinets for holding and displaying photographs or other pictures.

My object is to produce such a cabinet by which I am enabled to display several pictures at a time or groups of pictures successively; and to that end my invention consists in the several new and novel features of construction and operation hereinafter described and which are specifically set forth in the claims hereunto annexed.

It is constructed as follows, reference being had to the accompanying drawings, in which—

Figure 1 is a front view of my cabinet complete mounted upon legs, the legs being broken away. Fig. 2 is a top plan view thereof, a portion of the cover being removed, showing the interior mechanism. Fig. 3 is an enlarged detail of one of the folding picture-holders. Fig. 4 is a vertical section of one-half of the interior of the cabinet.

Similar letters of reference indicate corresponding parts.

a is a circular body having an opening *a'* in front affording a view of the interior, the body being supported by legs *a''* or in any other suitable manner and is provided with a removable top *b*. The opening *a'* may also be provided with a cover or door for the purpose of keeping the dust or foreign material from getting inside.

The bottom of the cabinet *c* is provided upon its upper face with a groove *c'*, near the outer edge, for the purposes hereinafter set forth.

d are picture-holding devices and may be constructed in any manner desired, so that they hold the picture in an upright position. This may be done either by securing the picture to the body or providing it with an opening and securing the picture to the back of

it, so that it may be observed through the opening. Two of these picture-holders are hinged together at *d'*, at their adjacent ends, and are hinged or loosely secured together at their outer ends to the upright or support *e*. The upright *e* is an ordinary rectangular piece of wood or similar material slightly curved in horizontal cross-section, as shown in Fig. 3, the lower end adapted to travel in the groove *c'*. I provide the cabinet with as many of these picture-holders, secured together as above described, as the cabinet will conveniently hold, so that by moving the uprights *e* apart I throw the picture-holders in the position shown in Fig. 3, where they may be viewed. When it is desired to pass this by, I move one of the uprights toward the other, when it folds up, as shown in Fig. 2. The uprights may then be pressed against one another, and as they pass around in the groove a new group will be presented to view.

The rear ends of the picture-holders are supported by an upright *e'* or in any other suitable manner.

Having described my invention, what I claim, and desire to secure by Letters Patent, is—

1. A cabinet, having an opening in one of its faces, a bottom provided with an annular groove, and picture-holders hinged together at their adjacent ends, and hinged to uprights, adapted to travel in said groove, as set forth.

2. A cabinet, comprising a body having an opening in one of its faces, and a bottom having an annular groove, picture-holders provided with means for holding pictures, hinged together at their adjacent ends, the opposite ends being hinged to uprights, said uprights being adapted to travel in said groove, and means for supporting the inner ends of the picture-holders, substantially as described for the purposes set forth.

In witness whereof I have hereunto set my hand this 14th day of May, 1898.

GEORGE HEIMLICH.

In presence of—

HOWARD P. DENISON,
MARY A. FRANKLIN.
